UNITED STATES PATENT OFFICE.

ALFRED L. CLARK, OF DUBUQUE, IOWA.

FIRE-ESCAPE.

SPECIFICATION forming part of Letters Patent No. 292,411, dated January 22, 1884.

Application filed June 12, 1883. (No model.)

To all whom it may concern:

Be it known that I, ALFRED L. CLARK, of Dubuque, in the county of Dubuque and State of Iowa, have invented a new and useful Improvement in Fire-Escapes; and I do hereby declare that the following is a full, and exact description of the same, reference being had to the accompanying drawings, and to the letters of reference marked thereon.

10 My invention relates to an improvement in friction-blocks, and has special reference to that class known as "friction-escapes."

15 The object in view is to render such an escape durable and effective by giving the rope an even tension along its bearing-surface, in order that frictional wear will not occur more rapidly at one point than at another; and to this end the invention consists in the novel construction of the device, all as more fully 20 hereinafter described and claimed.

For the better understanding of the invention, reference will be made to the accompanying drawings, in which—

Figure 1 is a front elevation of the device 25 complete, and Fig. 2 a side view of the same.

Like letters refer to like parts in both views.

In the drawings, A represents a metal block, consisting of plates *a a* and intervening 30 studs B B and C, all cast in one piece. The central stud, C, is preferably cylindrical in form, and the studs B B semi-cylindrical, the periphery of each of said studs being preferably grooved to assure a more certain guide 35 for the rope D, hereinafter referred to. The periphery of these studs may, however, if desired, present a flat surface. At each end of the block A there is formed an eye, *b*, the object of which will be mentioned. At or about 40 the center of this block, and passing through the stud C, is a hole, *c*, which is preferably cylindrical in form, and through which is passed a belt, E, upon which the operator of the device is supported. This belt E is 45 formed of any suitable material, and has its ends suitably joined together, so as to form an endless belt. It is provided with a movable loop, *d*, by means of which it is adjusted to the body of different operators. The rope 50 D, before referred to, is passed through one

of the eyes *b*, formed one on each end of the block A, then passed over the grooved periphery of one of the studs B, and around the cylindrical stud C, thence over the remaining stud, B, and through the second eye *b*. 55 This rope is provided at each end with a loop, X, or other suitable means, for securing it to the building upon which the escape is to be used.

The operation of the device is as follows: 60 The rope D is secured to the building or to any article of furniture in the room from which the person desires to escape, and is of sufficient length to reach the ground. The person in danger then passes the endless belt 65 E around his body, adjusting the movable loop *d* as required, the weight of his body causing the block A to descend. The rapidity of the descent can be regulated by the person using the escape or by any one on the 70 ground by simply pulling upon the rope at some point below the block A.

When the escape has been used and the block A is at the ground, the entire rope is drawn up and the end, which in the first instance hung loosely, is secured to the building, 75 and the escape is again ready for use.

By having the supporting-belt secured to the block at about the center thereof it is not necessary to change the position of said belt 80 after the escape has once been used; and, further, by having this belt passed through and over the stud upon which the rope is wound, all danger of the person's falling in case of the breakage of the block is avoided, because 85 of the fact that the belt will be caught by and supported on the rope itself.

I have found that by the construction of the block described, and by the arrangement and construction of the studs with which said 90 block is provided, perfect friction is obtained, and all danger arising from a too rapid descent is avoided and a perfect escape obtained.

Having described my invention, what I claim 95 as new therein, and that for which I desire to secure Letters Patent, is—

In a friction fire-escape, and in combination with the rope D, the block A, having grooved end eyes, and consisting of two 100

plates, *a a*, provided with an intermediate central and cylindrical stud, *C*, and two intermediate end studs, *B B*, semicircular in form, and having grooved peripheries, whereby an even tension is given that portion of the rope passing through the block, substantially as set forth.

In testimony whereof I affix my signature in presence of two witnesses.

ALFRED L. CLARK.
